CONVERTIBLE DUPLEX SIMPLEX PRINTING
TELEGRAPH SYSTEM

Joseph N. Loop, Washington, D. C.

Application April 9, 1936, Serial No. 73,525

17 Claims. (Cl. 178—58)

My invention relates broadly to printing telegraph systems and more particularly to a convertible differential duplex-simplex printing telegraph system.

5 One of the objects of my invention is to provide a system whereby automatic printers may be operated either duplex or simplex at the election of the operators.

10 Another object of my invention is to provide a simplified circuit for automatic printing telegraph systems which may be operated through the usual concentrator boards either duplex or simplex with a simple switching means for determining either condition of operation of the system.

15 Still another object of my invention is to provide a balanced circuit arrangement for a printing telegraph system by which either duplex or simplex operation may be effected without disturbing the balanced operation of the circuit.

20 A further object of my invention is to provide a circuit arrangement for a printing telegraph system in which a switching device is provided adjacent each automatic printer in the system, 25 which device is movable to either of two limiting positions for arranging the connections for the printers for either duplex or simplex operation at the will of the operators.

25 A still further object of my invention is to 30 provide a circuit arrangement for automatic printers each including a transmitter contact circuit and a printer magnet circuit whereby the transmitter contact circuit of one printer may be employed for operating both of the printer magnet 35 circuits of the printers or in which the transmitter contact circuits of the respective printers may be selectively employed for operating only the printer magnet circuit of the opposite printer for duplex operation of the system.

40 Other and further objects of my invention reside in a convertible duplex-simplex printing telegraph system as set forth more fully in the specification hereinafter following by reference to the accompanying drawing which diagrammatically and schematically illustrates a preferred embodiment of the system of my invention.

45 My invention is directed to a printing telegraph system in which the capacity during hours of rush business may be doubled. The system may 50 be operated through the usual concentrator boards, and motors on the automatic printers may be controlled in the customary manner. However, instead of the usual one-way operation normally employed in simple printer circuits, I 55 provide means whereby, in hours of rush busi-

ness, the circuit may be converted to differential duplex operation independently of the balanced condition of the circuit for simplex operation and business passed simultaneously in both directions over the line wire system. Such conversion of the system selectively and instantaneously from simplex to duplex permits rush of business to be disposed of promptly and economically. After the accumulation of business has subsided, the system may be readily switched back to simplex 10 operation prepared for instantaneous conversion to duplex operation as conditions demand.

5 Referring to the drawing in detail, I have indicated an interconnecting automatic printer circuit comprising an installation at a central office 15 marked A, interconnected with an installation at a branch office marked B. The automatic printer installations are adapted to be mounted on suitable operating tables, which carry the several parts of the equipment which I have schematically indicated. The automatic printer at central station A, has been illustrated as comprising a transmitting keyboard 1, adapted to operate start-stop contacts 2 for the transmission of signal impulses representing the numbers 20 and characters adapted to be transmitted from central station A. The automatic printer at station A, includes the set of magnetic windings 3, 25 controlling the mechanical printer through movable armature, indicated at 4. Associated with the transmitter contacts 2, and the mechanical windings 3, I provide a double throw multiple pole switch 5. The switch 5 includes a multiplicity of pivoted arms, which I have indicated at 6, 7, 8 and 9, interconnected by an insulated 30 member 10, which is pivoted centrally at each of the arms 6, 7, 8 and 9. The central switch arms are movable to either of two limiting positions at the right or left. In the right hand position, 35 illustrated in full lines, switch arms 6, 7, 8 and 9, establish connection with contacts 11, 12, 13 and 14. In the other limiting position, that is, toward the left, switch arms 6, 7, 8 and 9 establish connection with contacts 15, 16, 17 and 18. For the purpose of explaining my invention, it 40 will be noted at this time, that the right hand position of the multiple pole switch is the simplex operating position, the position now illustrated in full lines, whereas the left hand position of the switch is the duplex operating position.

45 Referring now to the branch station B, it will be seen that an automatic printer 85 is provided which is similar to the printer at central station A, in that it includes a transmitter contact circuit 86 and a printer magnet circuit 47. A 50 55

break button switch 48 is provided in circuit with the transmitter contact circuit 86, for opening the line for purposes of signaling the central station A, through the connection to ground 49. 5 A polarized relay 50 is provided, having actuating windings 51-52 and 53-54 similar to the actuating windings of the polarized relay at central station A. A switch 55 is provided at station B, corresponding to switch 5 at station A. Switch 10 55 includes movable arms 56, 57, 58 and 59 interconnected by insulated member 60, centrally pivoted to the switch arms for the purpose of shifting the switch arms simultaneously to either of two limiting positions. The position shown in 15 full line to the right is the simplex operating position. When moved to the left, the switches are disposed in duplex operating position. The sets of contacts utilized for the simplex operating position of the switch are designated at 61, 20 62, 63 and 64. The contacts which are employed for the duplex operating position of the switch are represented at 65, 66, 67 and 68.

Relay bias circuit at central station A is 110 volts through resistance 34, switch arm 8, contact 25 13, coil 36-37 of relay 24, resistances 38 and 39 to ground 40 at approximately .030 amp. Relay bias at branch station B is 110 volts through resistance 69 dividing into two circuits, one through resistance 70 to ground 49, the other 30 through resistance 71, coil 51-52 of relay 50, switch arm 58, contact 63, to ground 72, coil 51-52 receiving approximately .030 amp. A direct current source, such as a battery or a generator 19, is provided at central station A. 35 In simplex operation, the source 19 supplies line current. The signal circuit then connects from source 19 through resistance 21, contact 14, switch arm 9, transmitter contacts 2, coil 22-23, concentrator board 25 to line 26, thence through 40 motor control relays 76, contact 64, switch arm 59, coils 54-53, transmitter contacts 86, closed switch 48 to ground at 49, at approximately 70 milliamperes. Contacts 2 and 86 may be used alternately to transmit signals which are printed 45 at both stations as the current impulses pass through coil 53-54, and coil 22-23.

As source 19 alone supplies line current during simplex operation, the polarity of the source 19 with respect to source 46 at station B is immaterial. In duplex operation, however, the polarity of the sources 19 and 46 must be the same so as to maintain the line at a neutral potential. I have shown positive potential applied to the system, but it is entirely possible to reverse the polarity and provide negative potential provided both pairs of relay contact leads are first transposed (71-79 and 28-33). The source 19, at central station A, connects to ground 29 at one side, and through resistance 21 to switch contact 14 at the 60 other side. When switch 5 is thrown to the right, as illustrated, switch arm 9 provides a conductive path from contact 14 through transmitter contacts 2 and winding 22-23 of the polarized relay 24, through concentrator board 25 to the line 26. 65 The printer magnet circuit at station A, which includes magnetic windings 3, is actuated from the source 19, and controlled through tongue 27, and the contact 28 of the polarized relay 24. One side of the selector magnet 3, connects to contact 70 28. The other side of the selector magnet 3, connects to ground 29. A circuit for reducing sparking at the relay make and break, is provided in shunt with tongue 27 and contact 28, including resistance 38 and condenser 31. A resistance 75 32 is connected in the circuit from the power

source 19. The local circuit, through selector magnet 3, is complete through ground connections 20 and 29.

The local printer circuit at station B operates through source 46, resistance 80, tongue 78 and 5 either contact 77 or contact 79 of relay 50, through switch arm 56, printer magnet windings 47, and ground connections 49 and 45. The printer magnets at stations A and B are thus operated through the relays 24 and 50, respectively, and not directly from the line. 10

In describing now the duplex operation of the system, the switches 5 and 55 will be assumed to be thrown to the left hand positions. It will be noted that the polarities of the sources 19 and 46 are alike, as required, and that in duplex operation, the motor control relays at 76 are disconnected and the bias circuits are incorporated in the duplex system. In the duplex arrangement, it will be further noted, the transmitter contacts 20 2 and 86 are both connected with ground at one side.

Considering closed circuit conditions prevailing with both terminals idle, the circuit at station A may be traced from source 19 through resistor 34, to switch arm 8. Switch arm 8 is movable to either of two positions. In the position shown, which is the simplex position, the circuit is complete as a simple bias circuit from contact 13 through winding 36-37 of the polarized relay 24, returning through resistance 38 and through resistance 39 to ground 40, returning to source 19 through ground 29. When switch 5 is moved to duplex position, switch arm 8 is shifted to contact 17. The circuit then continues through contact 17, branches into one path through resistance 39 to ground 40, and another through resistance 38 and winding 37-36 of polarized relay 24, connected to contact arm 7, which is resting on contact 16. Beyond 16, the 40 circuit is joined by the path through contact arm 6, resting on contact 15, and through resistance 41 from one side of the source 19, and connects through lead 42, transmitter contacts 2, lead 43, and switch 9 to ground at 44. Both transmitter 45 contacts 2 and 86 being closed, the line 26 is grounded at both ends, and is neutral, and no current flows through coil 22-23 to the line. 35

The corresponding conditions at station B are as follows. The source 46 connects through 50 resistance 69 dividing through two paths, the one through resistance 70 to ground 49, and the other through resistance 71 through relay winding 51-52 of polarized relay 50 to switch arm 58. In the simplex operating position, the circuit is 55 complete as a simple bias circuit through contact 63 and ground 72 to ground 45 returning to source 46. In the duplex operating position, with contacts 2 and 86 closed, the circuit continues from arm 58, contact 67, through resistance 73, 60 through lead 83, and is joined here by another circuit comprised of lead 74, contact arm 57, contact 66, resistance 75, connected to one side of source 46. The combined circuits are completed through the transmitter contact circuit 65 86, break button switch 48, and ground 49. No current flows through winding 53-54 because the line circuit 26 is neutral. Both windings 51-52, and 37-36, at stations B and A respectively, receive the marking current. 70

As indicated, I employ the motor control relays shown generally at 76 for simplex operation only, though provision may easily be made for motor control relays in the duplex circuits. Relay 50 operates printer magnet 47 through con- 75

tact 77, coacting with tongue 78 of relay 50, instead of through contact 79 due to changed bias conditions at station B for duplex operation. The bias circuits for both stations become part of the duplex circuits, as will be clearly understood as the description progresses.

The local printer magnet circuit for station B includes resistance 80, which is connected at one side to source 46, and at the other side to tongue 10 78 of polarized relay 50, operative between contacts 77 and 79. The spark reducing circuit, which includes resistance 81 and condenser 82 is effectively connected in shunt with the contacts which are in actual use during any given operating period.

Tracing the circuits through the two stations connected for duplex operation, it will be clear that when both transmitter contact circuits 83 and 2 are open, the current conditions at central 20 station A are: 110 volts source 19, through resistance 41, switch contact 15, switch arm 6, switch contact 16, switch arm 7, winding 36-37 of polarized relay 24, resistance 38, joined here by another circuit comprising contact 17, switch 25 arm 8, resistance 34, connecting to source 19, thence combined through resistance 39 to ground 40. Inasmuch as line 26 is neutral, there is no current flow through winding 22-23. At the branch station B, the circuit may be traced from 30 the 110 volt source 46, through resistance 75, contact 66, switch arm 57, conductor 74, lead 83, resistance 73, contact 67, switch arm 58, winding 52-51 of polarized relay 50, resistance 71, joined here by 110 volts from source 46 through 35 resistance 69 and thence through resistance 10 to ground 49. There is no current in winding 53-54 of polarized relay 50. The windings 52-51 and 36-37 of the respective relays 50 and 24 are both passing spacing current, with 40 the contacts at 2 and 86 open.

With transmitter contacts 2 at station A closed, and transmitter contacts 86 at station B open, current flows from source 46 at station B through resistance 69, dividing through the one path including resistance 10 to ground 49, and through 45 the other path continuing through resistance 71, winding 51-52 of relay 50, switch arm 58, contact 67, resistance 73, conductor 83, joined here by the 110 volt source through conductor 74, switch arm 57, contact 66, and resistance 75, 50 and thence through windings 53 and 54 of relay 50, switch arm 59 and contact 68 to line 26. That is to say during duplex operation the motor control relays 76 are shunted out. The winding 55 51-52 of polarized relay 50, receives a small spacing current, while winding 53-54 receives a large marking current causing the relay to be marked.

At the central station A the same conditions 60 prevail as described for both transmitter contacts 2 and 86 closed, with winding 36-37 receiving marking current, excepting that winding 23-22 of polarized relay 24 now receives the current from line 26, terminating in ground 65 through transmitter contacts 2, conductor 43, switch arm 9, contact 18 and ground 44. The winding 23-22 of relay 24 receives the same current value as is passed through winding 53-54 of polarized relay 50, but in reverse order, being 70 spacing in polarized relay 24.

Exactly the same conditions occur when transmitter contacts 2 at station A are open, and transmitter contacts 86 at station B are closed, except that circuit conditions are reversed end for 75 end.

All that is necessary in converting the system from simplex operation to duplex operation, is to shift switches 5 and 55 from the right to the left, which may be very quickly accomplished, allowing traffic to flow in opposite directions over the line 5 26 simultaneously.

I provide a jack switch 84 for establishing connection with the local circuit of printer 85 for taking local copy if desired.

I have found the following values of different 10 elements in the system of my invention particularly efficient:

26	line resistance approximately	1000 ohms
73-21	resistance	600 ohms
75-41-80-82	do	1500 ohms
70-39	do	800 ohms
38	do	1000 ohms
81-30	do	150 ohms
71	do	400 ohms
69-34	do	2000 ohms
82-31	condenser capacity	1/2 mf.

The following table indicates the current conditions in a typical installation embodying my invention:

Key		Current values in milliamperes observed at Station A						
Station B	Station A	Bias winding		Line winding		Total		30
		Marking	Spacing	Marking	Spacing	Marking	Spacing	
Closed	Closed	20	0	0	0	20	0	35
Do	Open	8	40	40	40	32	20	
Open	Closed	20	40	40	40	20	20	
Do	Open	28	0	0	0	28	28	

Thus, it will be seen that the marking impulses at the receiving station, in duplex operation, are the result of a differential of current in the windings of the polarized relay. In line 1 of the above table of current values, therefore, a marking current of 20 milliamperes is effective at the receiver (station A) though no line current is flowing. 40 The same holds true for the spacing impulse in the last line. In each of these instances the bias winding becomes the actuating winding for recording the signal impulse. In each of the intermediate two lines of the table, the signal current is the differential of the line and the bias currents; and, in this example, is effective 45 through the line winding of the relay.

I have found the system of my invention highly practical, efficient and economical. While I have described my invention in one of its preferred embodiments, I realize that changes and modifications may be made, and I accordingly intend no limitations upon my invention other than 50 may be imposed by the scope of the appended claims.

What I claim as new and desire to secure by Letters Patent of the United States is as follows:

1. A convertible duplex-simplex printing telegraph system comprising a single line wire circuit, printing telegraph sets located at spaced intervals along said line wire circuit, each of said printing telegraph sets including a printer magnet circuit, and a transmitter contact circuit, relays interconnecting said circuits with the single line wire circuit, switching means connected with said relays, said printer magnet circuits and said transmitter contact circuits, said switching means being movable to either of two limiting positions for causing in one limiting 70 75

- position the transmitter contact circuit of one printer set to be effective through said relays on the printer magnet circuit of both of said sets, and in the other limiting position the transmitter contact circuit of one printer set to be effective through said relays only on the printer magnet circuit of another of said printer sets, through said single line wire circuit.
5. In a convertible duplex-simplex printing telegraph system, a pair of intercommunicating printer telegraph sets each including a printer magnet circuit and a transmitter contact circuit, a single line wire circuit for interconnecting said sets, and means for selectively operatively relating the transmitter contact circuit of one printer set with the printer magnet circuits of both of said printer telegraph sets under one condition and selectively operatively relating the transmitter contact circuit of either of 10 said sets exclusively with the printer magnet circuit of the opposite printer set under another condition, through said single line wire circuit.
6. In a convertible duplex-simplex printing telegraph system, a pair of intercommunicating printer telegraph sets each including a printer magnet circuit and a transmitter contact circuit, a single line wire circuit for interconnecting said sets, means for selectively operatively relating the transmitter contact circuit of one printer set 15 with the printer magnet circuits of both of said printer telegraph sets under one condition and selectively operatively relating the transmitter contact circuit of one of said sets exclusively with the printer magnet circuit of the opposite printer set under another condition, and resistances disposed in said circuits for balancing for operation all of said circuits independently of the arrangement effected by the said last mentioned means.
7. In a convertible duplex-simplex printing telegraph system, a pair of intercommunicating printer telegraph sets each including a printer magnet circuit and a transmitter contact circuit, a single line wire circuit for interconnecting said sets, and a multi-pole switch individual to each of said printer sets and connected with said circuits, said switches being movable to either of two limiting positions for operatively relating in one limiting position the transmitter contact circuit of one printer set with the printer magnet circuits of both the printer sets and operatively relating in the other limiting position the transmitter contact circuit of either printer set exclusively with the printer magnet circuit of the opposite printer set, through said single line wire circuit.
8. In a convertible duplex-simplex printing telegraph system, a pair of intercommunicating printer telegraph sets each including a printer magnet circuit and a transmitter contact circuit, a single line wire circuit for interconnecting said sets, a multi-pole switch individual to each of said printer sets and connected with said circuits, said switches being movable to either of two limiting positions for operatively relating in one limiting position the transmitter contact circuit of one printer set with the printer magnet circuits of both the printer sets and operatively relating in the other limiting position the transmitter contact circuit of one printer set exclusively with the printer magnet circuit of the opposite printer set, and means for balancing for operation all of said circuits independently of the position of said switches.
9. In a convertible duplex-simplex printing telegraph system, a pair of intercommunicating printer telegraph sets each including a printer magnet circuit and a transmitter contact circuit, a single line wire circuit for interconnecting said sets, a multi-pole switch individual to each of said printer sets and connected with said circuits, said switches being movable to either of two limiting positions for operatively relating in one limiting position the transmitter contact circuit of one printer set with the printer magnet circuits of both the printer sets and operatively relating in the other limiting position the transmitter contact circuit of one printer set exclusively with the printer magnet circuit of the opposite printer set, and resistors disposed in said circuits for balancing for operation all said circuits independently of the position of said switches.
10. In a printing telegraph system, including a single line wire circuit, printing telegraph sets connected with said line wire circuit in coacting relation, means for operating said sets simplex, means for operating said sets duplex, and means separately connected with each of the aforesaid means for altering the coacting relation of said sets in connection with said single line wire circuit for rendering either of said means operatively effective at different times.
11. In a printing telegraph system for single line operation, an arrangement for duplex operation which comprises a transmitter contact circuit and a printer magnet circuit at each of two stations, each transmitter contact circuit being connected with said line, and means for controlling the printer magnet circuit at either station by the coaction of the transmitter contact circuits at both stations through said line.
12. In a printing telegraph system for single line operation, an arrangement for duplex operation comprising a transmitter contact circuit and a printer magnet circuit at each of two stations, each transmitter contact circuit being connected with said line, means for actuating the printer magnet circuit at each station from the transmitter contact circuit at the respective station, and means for controlling the transmitter contact circuit at one of said stations and correspondingly controlling the printer magnet circuit at the same station by the transmitter contact circuit at the other of said stations through said line.
13. In a printing telegraph system for single line operation, an arrangement for duplex operation comprising a transmitter contact circuit and a printer magnet circuit at each of two stations, a polarized relay at each station adapted to control the respective printer magnet circuit, each said relay including a pair of differentially wound coils, means for connecting one coil of each said relay with the respective transmitter contact circuit, and means for connecting the other coil of each said relay with both said transmitter contact circuits, whereby each said relay is actuated by the differential of two currents, one in each of said coils.
14. In a printing telegraph system for single line operation, including a transmitter contact circuit and a printer magnet circuit at each of two stations, each transmitter contact circuit being connected with said line, means for operating said stations simplex by directly controlling the operation of both said printer magnet circuits by either of said transmitter contact circuits through said line, means for operating said stations duplex by controlling the operation of

either of said printer magnet circuits by the co-action of both said transmitter contact circuits through said line, and means for rendering either of said means operatively effective at different times.

12. In a printing telegraph system for single line operation, including a transmitter contact circuit and a printer magnet circuit at each of two stations, a polarized relay at each station adapted to control the respective printer magnet circuit, each said relay including a pair of differentially wound coils; means for operating said stations simplex, comprising means for biasing one coil in each said relay, and means for controlling the operation of both said printer magnet circuits by either of said transmitter contact circuits through the other coil of each said relay; means for operating said stations duplex, comprising means for connecting the bias coil of each relay with the respective transmitter contact circuit, and means for connecting the other coil of each relay with both said transmitter contact circuits, whereby each said relay is actuated by the differential of two currents, one in each of said coils; and multi-pole switching means at each of said stations for cooperatively effecting a change from simplex operation to duplex operation or vice versa.

13. In a printing telegraph system for single line operation, an arrangement for simplex operation comprising a transmitter contact circuit and a printer magnet circuit at each of two stations, and a polarized relay at each station adapted to control the respective printer magnet circuit, each said relay including a pair of differentially wound coils; and separate switching means in circuit with one of the relay coils, said transmitter contact circuit, and said printer relay circuit at one of said stations, and with one of the relay coils, and said transmitter contact circuit at the other of said stations, for altering said arrangement for simplex operation to facilitate an arrangement for duplex operation.

14. In a printing telegraph system for single line operation, an arrangement for duplex operation as set forth in claim 10, and separate switching means in circuit with the first said relay coil, said transmitter contact circuit, said printer relay circuit, and the first said means at

one of the stations, and with the first said relay coil, said transmitter contact circuit, and in plurality in the first said means at the other of the stations, for altering said arrangement for duplex operation to facilitate an arrangement for simplex operation.

15. In a printing telegraph system, an arrangement for duplex operation comprising a transmitter contact circuit and a printer magnet circuit at each of two stations, means at each station for controlling the respective printer magnet circuit, each said means constructed to be operative by the differential of two currents, means for producing said currents, one a bias current supplied locally, and the other a signal current controlled by the transmitter contact circuit at the remote one of said stations, and means for balancing in the first said means the signal current controlled by the local transmitter contact circuit.

16. In a printing telegraph system, an arrangement for simplex operation comprising a transmitter contact circuit, a printer magnet circuit at each of two stations, and means at each station for controlling the respective printer magnet circuit, each said means constructed to be operative by the differential of two currents, and means for producing said currents, one a bias current supplied locally, and the other a signal current controlled by the transmitter contact circuit at either of said stations; said arrangement including switch means connected with said circuits and with the last said means for applying other currents to the aforesaid means for varying the operation of said system.

17. In a printing telegraph system, a transmitter contact circuit and a printer magnet circuit at each of two stations, means at each station constructed to be operative by the differential of two currents for controlling the respective printer magnet circuit, and separate means at each station for selectively providing the two currents effective on the aforesaid means for determining the nature of the differential currents in regard to the respective transmitter contact circuits for establishing the character of operation, simplex or duplex, of the system.

JOSEPH N. LOOP.
